SAFETY WINDOW PLATFORM

Application filed August 29, 1929. Serial No. 389,194.

This invention relates to safety platforms for windows to support mechanics, window-washers, and the like, and has for its object the production of a knockdown platform which may be quickly put together when its use is desired.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a rear elevation of a platform embodying the principles of the present invention.

Figure 2 represents a section of same on line 2, 2, on Fig. 1, and shown applied to a window frame.

Figure 3 represents a plan of same applied to a window frame.

Figure 4 represents a section of the device for making connection with the cross bar on the inner face of the window frame.

Figure 5 represents a section on line 5, 5, on Fig. 4.

Figure 6 represents a section of the cross bar on line 6, 6, on Fig. 2.

Figure 7 represents a section on line 7, 7, on Fig. 3, and

Figures 8 and 9 represent respectively an elevation and inverted plan of one of the supporting boards.

Similar characters indicate like parts throughout the several figures of the drawings.

In the drawings, 10 is a horizontal metal tubular member and 11 an inclined metal tubular member, the member 11 having a metal connection 12 inserted into the outer end thereof from which a cylindrical stem 13 extends upwardly through the outer end

of the tubular member 10 and is secured thereto by a pin 14.

Surrounding the stem 13 is a metal tube 15.

The lower end of the inclined tubular member 11 extends into a socket in a hub 16 formed upon one face of the metal plate 17 having on its opposite face a sheet 18 of resilient material adapted to rest against the outer wall 19 of a building.

Between the horizontal tubular member 10 and inclined member 11 are a plurality of metal braces 20, the opposite ends of which are welded to said tubular members.

Between these braces 20 and welded thereto are horizontal supports 21.

Upon these supports 21 are disposed supporting boards 22 provided on the under side with cleats 24 at the opposite ends thereof contacting with the supports 21 and preventing end movement of said boards.

Each board 22 has another cleat 25 on its under side which may coact with one of the supports 21 when the side frames 10, 11 are moved toward each other to fit a narrow window.

Between the side frames 10, 11 is a cross rod 26 having downturned ends 27 which may be inserted into the upper ends of the metal tubes 15 and retain the side frames at proper distances apart.

The cross rod 26 has other projections 28 closer together and adapted for insertion into the upper ends of the metal tubes 15 when the platform is to be adjusted for a narrow window frame.

The horizontal tubular member 10 is provided with a rubber sleeve 29 which is adapted to rest upon the sill of a window frame, this resilient material preventing the sill from being marred when the platform is in use.

Inserted into one end of each horizontal tubular member 10 is the head 30 of a threaded rod 31, this head 30 being square and fitted to the bore of said tubular member 10.

A pin 32 extending through the head and the side walls of the tubular member 10 prevents said threaded member 31 from being displaced.

Within the building is a tubular metal cross bar 33 having holes 34 extending therethrough to receive the threaded rods 31 on each of which are mounted the adjustable 5 clamp nuts 34.

The opposite ends of the cross bar 33 have sleeves 35 of resilient material which are adapted to contact with the inner faces of the window frame 36 to prevent said faces 10 from being marred when the platform is in use.

The boards 22 are at various levels and the upper board rests upon the horizontal tubular members 10.

15 By having these supporting boards at different levels the person using the platform may stand or sit on either board according to the work being performed. The cross rod 26 not only keeps the side frames at the 20 proper distance apart but serves as a back rest when the upper board 22 is being used.

The device may be readily set up and positioned on a window frame and building as indicated in Fig. 2 without injuring any 25 part of the building or window frame and when not in use it may be quickly dismembered and will occupy very little space when being transported from one position to another.

30 It is obvious also that the platform may be adjusted to accommodate it to various widths of windows.

By making the side frames of tubular metal members connected by brace rods welded thereto, very rigid side frames are insured 35 capable of sustaining great weight.

The platform may be used by window washers, painters, carpenters and other mechanics, and when once installed may be 40 used with absolute safety.

It is believed that the operation and many advantages of the invention will be understood without further description.

Having thus described our invention, we 45 claim:

60 1. A window platform comprising two independent angular side frames having vertical braces and horizontal supports at different levels; boards disposed on said supports; a cross bar adapted to contact with the inner 65 faces of the sides of a window frame; means on said side frames for making connection with said cross bar at different points to vary the distance between said side frames; tubular projections extending upwardly from the rear ends of said side frames; and a cross rod having two sets of projections, either set being adapted to be disposed in said tubular 70 projections.

65 2. A window platform comprising two independent side frames consisting of horizontal tubular members, inclined tubular members connected thereto at their outer ends, and horizontal supports at different levels, plates having sockets to receive the lower

ends of the inclined tubular members; a cross bar adapted to contact with the inner face of a window frame; means on the front ends of the horizontal tubular members extending through and making connection with said 70 cross bar; a detachable connecting rod between the rear ends of the horizontal tubular members; supporting boards on said supports; and means whereby said side frames may be retained different distances apart. 75

3. A window platform comprising two independent side frames each consisting of a horizontal tubular member, and inclined tubular member connected thereto at its outer end, a plate at the lower ends of the inclined tubular members, and horizontal supports at different levels; a cross bar adapted to contact with the inner face of a window frame; means on the front ends of the horizontal tubular members for making connection with said cross bar at different points lengthwise thereof; a detachable connecting rod between the rear ends of the horizontal tubular members; and supporting boards on said supports; having a plurality of cleats 90 adapted to coat with said supports. 95

4. A window platform comprising two independent side frames each consisting of a horizontal tubular member, and inclined tubular member connected thereto at its outer end, a plate at the lower ends of the inclined tubular members, and horizontal supports at different levels; a cross bar adapted to contact with the inner face of a window frame; means on the front ends of the horizontal tubular members for making connection with said cross bar at different points lengthwise thereof; a detachable connecting rod between the rear ends of the horizontal tubular members; and supporting boards on 100 said supports. 105

5. A window platform comprising two independent side frames each consisting of a horizontal tubular member, and inclined tubular member connected thereto at its outer end, a plate at the lower ends of the inclined tubular members, and horizontal supports at different levels; a cross bar adapted to contact with the inner face of a window frame; means on the front ends of the horizontal tubular members for making connection with said cross bar; a detachable connecting rod between the rear ends of the horizontal tubular members; supporting boards on said supports at different levels; and means on said boards coacting with said supports to prevent end movement of said boards. 115 120

6. A window platform comprising two independent angular side frames having vertical braces and horizontal supports at different levels; a board disposed on each pair of said supports; a cross bar adapted to contact with the inner faces of a window frame; means on said side frames for making connection 125 130

nection with said cross bar at different points lengthwise thereof; tubular projections extending upwardly from the rear end of said side frames; and a cross rod having two sets 5 of projections differently spaced and either set adapted to be disposed in said tubular projections.

7. A window platform comprising two independent angular metal side frames having 10 metal vertical braces and horizontal supports at different levels and all welded together; a board disposed on each pair of said supports, said boards being provided with three cleats two of which are adapted to coact with 15 said supports to prevent end movement of said boards when said frames are differently spaced apart; a cross bar adapted to contact with the inner faces of the window frame; and means on said side frames for 20 making connection with said cross bar at different points lengthwise thereof.

8. A window platform comprising two independent side frames consisting of horizontal tubular members, inclined tubular members 25 connected thereto at their outer ends, plates having sockets to receive the lower ends of the inclined tubular members, and horizontal supports at different levels, a cross bar adapted to contact with the inner 30 face of a window frame; means on the front ends of the horizontal tubular members for making connection with said cross bar at different points lengthwise thereof; a connecting rod between and above the rear ends 35 of the horizontal tubular members and adapted to be connected thereto when said tubular members are differently spaced apart; and supporting boards on said supports and immovable endwise.

40 9. A window platform comprising two independent side frames consisting of horizontal tubular members, inclined tubular members connected thereto at their outer ends, plates having sockets to receive the 45 lower ends of the inclined tubular members, and horizontal supports at different levels, a cross bar adapted to contact with the inner face of a window frame; means on the front ends of the horizontal tubular members for 50 making connection with said cross bar at different points lengthwise thereof; vertical tubes extending upwardly from the outer ends of said horizontal tubular members; a connecting rod having two sets of differently 55 spaced projections, either set being adapted to be inserted in the upper ends of said tubes; and supporting boards on said supports.

10. A window platform comprising two 60 horizontal tubular members; inclined tubular members connected thereto at their outer ends; plates having sockets to receive the lower ends of the inclined tubular members; a cross bar adapted to contact with the inner 65 face of the window frame; means on the

front ends of the horizontal tubular members for making connection with said cross bar; connections disposed in said inclined tubular members and extending through the outer ends of said horizontal tubular members; a tube surrounding the upper end of each connection; a connecting rod between the rear ends of the horizontal tubular members having downward projections adapted 70 to be inserted in the upper ends of said tubes; horizontal supports on said inclined tubular members; supporting boards on said supports; and resilient members secured to the front faces of said plates.

11. A window platform comprising two independent side frames each consisting of a horizontal tubular member, an inclined tubular member connected thereto at its outer end, a plate at the lower end of the inclined tubular member, and a plurality of horizontal supports; a cross bar adapted to contact with the inner face of the window frame; means on the front ends of the horizontal tubular members for making connection with said cross bar; supporting boards on 80 said supports; and means for connecting together said side frames at different distances apart.

12. A window platform comprising two independent side frames each consisting of a horizontal tubular member, an inclined tubular member connected thereto at its outer end, a plate at the lower end of the inclined tubular member; a tubular metal cross bar adapted to contact with the inner faces of 90 the window frame; means for connecting the front ends of the horizontal tubular members to said cross bar at different distances apart; and other means for connecting together the rear ends of the horizontal tubular members at the same distances apart.

Signed by us at 294 Washington St., Boston, Mass., this 27th day of August, 1929.
